COMBINED WHISTLE AND WHIRLIGIG

Saul Stone, Fitchburg, Mass.

Application September 23, 1953, Serial No. 26,911

Term of patent 14 years

(Cl. D34—15)

Fig. 1

Fig. 2

Fig. 3

Fig. 1 is a front perspective view of a combined whistle and whirligig, showing my new design;

Fig. 2 is a front elevational view thereof; and

Fig. 3 is a fragmentary rear perspective view thereof.

The side not shown has substantially the same appearance as the side shown in Fig. 1.

I claim:

The ornamental design for a combined whistle and whirligig, as shown and described.
